UNITED STATES PATENT OFFICE.

MATTHEW W. LYNCH, OF MADISON, WISCONSIN.

LOCK-BUCKLE.

SPECIFICATION forming part of Letters Patent No. 695,404, dated March 11, 1902.

Application filed May 9, 1900. Serial No. 16,082. (No model.)

To all whom it may concern:

Be it known that I, MATTHEW W. LYNCH, a citizen of the United States, residing at Madison, in the county of Dane and State of Wisconsin, have invented a new and useful Improvement in Lock-Buckles, of which the following is a specification.

My invention relates to improvements in lock-buckles in which the frame of the buckle has a mortise to receive and carry a bolt or slide which is operated by a key and provided with a ledge to cover and retain the tongue and a vertical groove or notch to receive a pin for holding the bolt in the desired position in the frame; and the objects of my improvements are, first, to relieve the buckle-tongue from all end thrust when a lateral strain is put upon it, and, second, to provide a means for taking up the wear on the bolt and holding it in position when unlocked. I attain these objects by the mechanism illustrated in the accompanying drawings, in which—

Figure 1 is a vertical section through lines A B on the frame *a* and C D on the bolt *b*. Fig. 2 is a plan, partly in section, showing the positions of the bolt *b*, tongue *c*, and retaining or lock pin *f* when the buckle is unlocked. Fig. 3 is a rear edge view of the bolt *b*, showing the wing *g* for taking up the wear on the same. Fig. 4 is a bottom view of the bolt *b*, showing the cover or ledge *e* and the same cut away at *d*, also the take-up wing *g*, formed by milling a slot from the notch *h* through to the key-channel *i*.

Similar letters refer to similar parts throughout the several views.

The frame *a* of my buckle is a rectangular plate upon both ends of which are formed loops, the one with the straight bar to be fastened to a buckle piece or strap and the one with the curved bar, being reduced in size at its center, is to carry the buckle-tongue. For the purpose of reference we will call the curved loop the "front end" of the buckle. To the center of the curved loop is fastened the tongue *c*, which is finished square across the end and of sufficient length to extend into a recess in the front end of the buckle-frame and rest upon a bearing on its lower edge. Horizontally through the buckle-frame *a*

near the front end is a mortise, and from the center of the mortise, extending nearly to the back of the frame, is a round hole. Into the mortise is fitted a flat bolt *b*, hereinafter more fully described, and into the round hole is placed a plug or lock-pin *f*, which is forced outward by a spiral spring. (See Fig. 1.) The flat bolt *b* is formed by cutting out of its front side the groove *d*, Figs. 2 and 4, and 60 milling away a portion of its rear lower corner, leaving the ledge *e*, Figs. 1 and 4. Then a key-channel *i* is cut from end to end on the front side, Figs. 1 and 3, and the notch *h* is formed by removing the central portion of 65 the two sides of the channel. On the bottom of the said bolt *b* a longitudinal slot is cut from the notch *h* toward the end and intersecting the key-channel *i*, forming the wing *g*, which is bent outward, and being elastic 70 will take up any wear between the mortise and bolt and hold the bolt in position when unlocked. It is clear that the tongue *c*, being square across its end, and the ledge *e*, projecting over it horizontally, prevent any end 75 thrust from a lateral strain on the tongue when the buckle is locked, and thus prevent accidental unlocking of the buckle, and it is also plain that by bending outward the wing *g* on the bolt *b* any play between the bolt 80 and mortise could be taken up.

To unlock my buckle, a thin metal key is inserted into the key-channel, and the lock-pin *f* is forced back into the frame, and the bolt *b* is pushed through the mortise until 85 the ledge *e* passes from over the tongue *c*, as shown in Fig. 2. To lock, remove the key and push the bolt *b* into the frame until the two are flush, when lock-pin *f* will drop into notch *h*.

I am aware that lock-buckles similar to this one described have been known and used before, with the exception of the arrangement for preventing end thrust and taking up the wear on the bolt.

I therefore only claim as new the following:

1. The combination in a lock-buckle, of a flat bolt having horizontal projecting ledge *e* and oppositely-disposed outwardly-projecting elastic wing *g* and notch *h*, a lock-pin 100 adapted to engage said notch, and a buckle-tongue *c* adapted to be engaged by said ledge

when the parts are in their locked position, as set forth.

2. The combination, in a lock-buckle, of a flat bolt having projecting ledge *e* extending horizontally, and a key-channel *i* upon the opposite edge extending from end to end and a notch *h* formed in said channel, and an elastic wing *g*, a lock-pin adapted to engage in said notch, and a buckle-tongue *c* over which

said ledge rides when the bolt is moved into its locked position, substantially as described.

In testimony whereof I have signed my name to this specification in the presence of two subscribing witnesses.

MATTHEW W. LYNCH.
